GENERATION OF ELECTRICAL IMPULSES CONTROLLED BY A PERFORATED CARRIER

Ulysse Baldé, Zurich, Switzerland, assignor to Mithra A.G., Zurich, Switzerland

Application September 21, 1954, Serial No. 457,456

Claims priority, application Switzerland June 23, 1954

14 Claims. (Cl. 235—61.11)

The present invention relates to a device for the generation of electric impulses, for example for the automatic control of calculating machines, machine tools, shaft machines on looms etc. For the generation of the electric control impulses as a rule electric contacts are opened and closed, for example in dependence of a rotating commutator, a punched tape, a magnetic tape etc. which runs over the circumference of a cylinder where the sensing of the tape is carried out.

It is an object of the present invention to provide a device for the generating of electric impulses in controlled dependence of a perforated carrier of the type known as punched card.

It is another object of the invention to provide a device of the kind referred to wherein any friction of brushes or any pressure of sensing pins on the said perforated carrier is obviated in order to eliminate the consequent wear and tear thereof and to make its availability for use practically indefinitely long.

It is yet another object of the invention to provide a device of the kind referred to wherein mechanically operated electrical contacts or commutators are obviated whereby the unavoidable wear and tear and the servicing consequently required thereof is eliminated.

With these and other objects in view, I provide a device for the generation of electric impulses in controlled dependence of a perforated carrier, comprising in combination: a rotatable hollow cylinder having a cylindrical wall, clamping means attaching the perforated carrier detachably to the circumference of the said hollow cylinder, the said hollow cylinder being provided with apertures corresponding in number and disposition to the possible places of perforation of the said carrier, at least one stationary source of light and a plurality of stationary photo-electric converters in juxtaposition to those apertures of the said cylinder which are disposed along a generatrix thereof, light-compartments separated from one another and each containing one of the said photo-electric converters, the said source of light and the said photo-electric converters being separated from one another by the cylindrical apertured wall of the said hollow cylinder.

These and other objects and features of my said invention will be clearly understood from the following detailed description of an embodiment thereof given by way of example with reference to the accompanying drawings, in which:

Fig. 1 is a vertical longitudinal section of the device,

Fig. 2 is a plan view thereof,

Fig. 3 is an end-elevation, partly in a vertical cross section with the hollow cylinder removed,

Fig. 4 is a detail of the device in cross section,

Fig. 5 shows the hollow cylinder detached, with the end pieces fixed thereto, in end-elevation,

Fig. 6 shows part of the hollow cylinder with a punched card clamped thereto, in cross section,

Fig. 7 shows an analogous cross section through another part of the cylinder,

2

Fig. 8 shows a punched card adapted for being clamped to the hollow cylinder, in elevation, and

Fig. 9 is a perspective view of an auxiliary device for the fixing of a card to the circumference of a hollow cylinder.

According to Figs. 1 to 3, the device has a supporting structure which consists of a base plate 101 and two vertically positioned plates 102 and 103 screwed thereto. In one of the vertical plates, 102, a stationary hub 104 is fixed with a horizontal axis. On this hub, by means of a ball bearing 105 and of a roller bearing 106, a ring 107 is journalled rotatably, which is provided on its circumference with a toothed 108. With the latter a gear wheel (not shown) can be brought into mesh for driving the ring 107. To the two end faces of the ring, lids 109 and 110 are screwed fixedly which enclose the anti-friction bearings 105 and 106, and protect the grease or oil serving for the lubrication of these bearings from being lost. On the ring 107 a further ring 111 is fixedly mounted which has a flange 112 projecting outwardly in order to prevent the lubricant to get from the toothed 108 to the right hand side in Fig. 1.

On the end, which in Fig. 1 is on the right hand side, a casing 113 is provided which consists of an integral piece of material with the said hub. In the interior of the casing 113 several incandescent bulbs 114 are fixed on an insulating body 115, which is provided with means for the electrical connection of the lamps 114. The electrical supply conductors 116 pass through an axial passage 117 of the hub and emerge through a radial opening thereof. On the insulating body 115 two reflector shields 118 are mounted which reflect the light of the lamps 114 upwardly. The casing 113 forms a diaphragm which has a slot 119 for the passage of the light. This slot runs parallel to the axis of rotation of the ring 107. The side of the casing 113 facing away from the hub 107 is closed by a perforated plate 120.

The casing 113 is surrounded with clearance by a hollow cylinder 121 on to which an end piece 122 is screwed, and another end piece 123 is pushed on detachably. For the attachment of the last mentioned end piece screws 124 are provided. The end piece 122 is according to Figs. 1 and 5, provided with three dogs 125 projecting inwardly between which recesses are left. The aforesaid lid 110, which is attached on the rotatable ring 104, has three dogs 126 of unequal width which project radially outward, and can engage between the dogs 125 of the end piece 122 of the cylinder. The dogs 125 and 126 form part of a so-called bayonet joint which permits the detachable attachment of the cylinder 121 on the ring 107. The dogs 125 and 126 can be brought into engagement with one another by an axial movement of the hollow cylinder 121, whereafter the cylinder with its end piece 122 is turned relative to the ring and its lid 110 about the axis of rotation of these components. Then the dogs 125 reach behind the dogs 126. The inner edge of the dogs 125 provided on the end piece 122 of the cylinder finds a suitable seat on a cylindrical face 127 of the lid 110 in such a manner that the cylinder 121 comes to lie coaxially to the rotatable ring 107. The ring 107 and the lid 110 fixed thereto form between themselves a rotatable holder for the hollow cylinder 121, in order that the latter may be supported, rotatable about its longitudinal axis. The cylinder 121 is then held at one of its ends only.

Into the ring 107 on the whole three bores are machined parallel to the axis of rotation, in each of which a cylindrical plunger 128 and a ball 129 is mounted shiftably. A compression spring 130 is likewise inserted into this bore and bears with one end on the plunger 128, and with its other end on the lid 109. Under the action of the spring 130 accordingly the ball 129 is forced in Fig.

1 towards the right against the adjacent dog 125 of the end piece 122 of the cylinder, so that the dogs 125 and 126 of the bayonet joint reaching behind one another are pressed against one another. When the cylinder 121 is separated from the holder 107, 110, the balls 123 bear on the dogs 126 of the lid 110, as shown in Fig. 3. One dog 125 is provided at its end face with a recess 131 (Fig. 5), in which one ball 129 rests under the action of the associated spring 130, when the end piece 122 of the cylinder has been brought into the appropriate closure position. Thereby any undesirable detaching of the components 110 and 122 from one another is prevented, and moreover always the same working position of the cylinder 121 in respect of the rotatable ring 107 is safeguarded. The components 128 to 130 form between themselves a spring device, which may alternatively have a construction different from that illustrated.

The hub 104 is provided with a second axial passage 133 going right through. Through this passage cooling air can be blown into the casing 113 to the lamps 114. The supply of air is effected through a pipe 134 which is screwed on to the hub 104, and which serves at the same time for restraining the same against axial displacement in one direction. The cooling air can escape through the perforated end plate 120 of the casing 113 and through holes 135 in the bottom of the end piece 123 of the cylinder. The cooling air passes through the interior of the hollow cylinder 121.

On the circumference of the hollow cylinder 121 a punched card 136 of conventional type is clamped. The card 136 has the rectangle shape shown in Fig. 8. The two longitudinal edges of the card run in the circumferential direction of the hollow cylinder 121 and are overlapped by the margins 127 of the two end pieces 122 and 123. In order to exchange the card 136, the end piece 123 is detached from the hollow cylinder. In order to secure further the position of the card 136 on the cylinder 121, the cylinder is provided with two pins 138 (Fig. 7) projecting radially outward, which are capable of engaging into two corresponding holes 139 of the card. The two edges on the short sides of the card are pressed according to Fig. 6 into a longitudinal groove 139 of the cylinder 121, namely by means of an auxiliary device 140, which is shown per se in Fig. 9. The middle portion of this device, which is of U-shaped profile, is pressed into the groove 139, while the end lugs 141 come to lie under the margins 137 of the end pieces 122 and 123.

According to Fig. 8, the card 136 used is divided into two horizontally running halves. In each half, holes may be arranged in forty five columns and six lines, a total of 6×90 holes. The 23rd and the 68th column, however, are not capable of being used in the present embodiment, since there the attachment holes 139 are arranged. Accordingly 88 columns only are usable. The wall of the hollow cylinder 121 is provided on its inside with longitudinal grooves 142, the number and position of which conforms with the columns 1 to 45 and 26 to 90, respectively, of the card 137 clamped on. Moreover the outer circumference of the cylinder wall is provided with circumferential grooves 143, the number and position of which corresponds with the lines, numbering twelve as a whole of the card 137. The longitudinal and circumferential grooves 142 and 143, respectively, are so deep that they make transition into one another and that square apertures are formed in the hollow cylinder at the crossing points. These apertures are located on those points, where the card 137 clamped on may have holes.

On the plate 103 of the supporting structure, by the aid of two holder bolts 145, a block 146 is fixed, which extends from the outer end of the cylinder 121 closely up to the circumference thereof, and to the punched card 137 clamped thereon. The block 146 extends over the whole length of the cylinder 121 and over a part of the circumference thereof, as clearly shown in Figs. 1 and 3. The block 146 is formed of several plates 147 stratified

side by side, which are held together by holder pins 145. Above the block 146, a body 148 is fixed, which consists of elastically resilient material, e. g. of sponge rubber, and which has twelve holes, each for taking in a photo-electric converter 149, e. g. a photo-electric cell. These photo-electric cells are arranged in three rows parallel to the axis of rotation of the cylinder 121, and are in echelon configuration with respect to one another, as clearly shown in Fig. 2. Into the block 146 several recesses 150 are machined which form light-passages separated from one another, each of which joins up with one of the photo-electric cells 149. These recesses 150 are machined each into one of the plates 147 forming the block 146. The orifices of the light-passages 150 facing away from the photo-electric cells lie all in a row parallel to the axis of rotation of the cylinder 121, namely opposite to the slot 119 of the casing 113 surrounding the lamps 114, and opposite to the 2×6 rows of the punched card 137 clamped on. Starting from these orifices, the light-passages flare out towards the photo-electric cells. On the block 146 moreover two insulating plates 151 are screwed fast, which are provided with contact pieces 152, on which the electrical conductors 153 are connected, which lead to the photo-electric cells 149. In Fig. 2 these conductors have been omitted, and in Fig. 3 are shown but partly, for clarity.

On the side of the cylinder 121 facing away from the block 146 a guide piece 154 is fixed on the plate 101 of the supporting structure. This guide piece 154, together with the block 146, facilitates the correct insertion of the hollow cylinder in relation to the rotary holder 107, 110. Of course neither the block 146 nor the guide piece 154 contacts the circumference of the cylinder 121 or the card clamped thereon, respectively, as soon as the cylinder is fixed to the rotatable holder 107, 110.

Over the upper portion of the block 146 a hood (not shown) is detachably placed, which prevents the access of light from the environment to the photo-electric cells 149.

The manner of use and of operation of the device described is as follows: the lamps 114 emit light through the slot 119 towards the inside of the hollow cylinder 121 and through the apertures thereof which are at any time situated over the slot 119. On places, where the punched card 136 clamped on is perforated, light can pass through the card and can fall on the associated photo-electric cells 149. In the latter thereby a potential difference is set up, which can be amplified and can be used for the electromagnetic control of any machines, relays etc. On those places where the punched card is not perforated, no light can fall on to the associated photo-electric cells. The photo-electric cells are accordingly energised in accordance with the holes present at any time in a column of the card 136.

When the card 136 is divided according to Fig. 8 into two halves, each of 44 usable columns, i. e. into a total of 88 usable columns of six rows each, a total of 88 control impulses can be derived from the card, in two revolutions of the cylinder 121. At the first revolution of the cylinder 121 only those current impulses are evaluated which are generated by the holes in the upper half of the card, and at the second revolution only those current impulses, which are generated by the holes in the lower half of the card. Each of these control impulses can be marked by one to six holes in the card. With one hole per column there result six different control possibilities, with two holes per column, fifteen different combinations, with four holes six of them, with five holes three of them, and with six holes one only. On the whole, accordingly forty one different control impulses can be recorded in one column.

Alternatively, the punched card can be divided into three zones running horizontally, each of which contains 44 columns of four rows. In this case in each column there result fifteen different control impulses. After three

consecutive revolutions of the hollow cylinder 121, in each of which one of the said zones of the card is evaluated by optical sensing, there result accordingly 3×44 , i. e. a total of 132 consecutive control impulses.

However, it is also possible not to divide the card into zones, and to arrange 44 columns of 12 rows on the same. The control impulses then repeat themselves after each revolution of the hollow cylinder.

Of course the device is not limited to the cards described by way of example, but could be arranged for the use of cards having a different number of lines and columns.

The apertures of the hollow cylinder coordinated to the possible holes of the cards need not be formed by intersecting longitudinal and circumferential grooves in the cylinder wall. It is also possible to produce the cylinder in a casting process in such a manner that the apertures are left free from the beginning on the right spots. The hollow cylinder could alternatively be stamped out of flat sheet material, and subsequently bent into the cylindrical shape.

Moreover other embodiments are conceivable, in which instead of the lamps 114 a single rod-shaped lamp is used as a source of light. Moreover at least one source of light could be arranged outside the hollow cylinder, and, in turn, the photo-electric converters in the interior of the hollow cylinder.

For each device, several hollow cylinders 121, each with its associated end pieces 122 and 123, could be used, and on each cylinder a differently perforated card 136 could be clamped. In this case it is possible, to exchange the cards together with the hollow cylinders carrying the same quickly, when a different sequence of impulses is intended to be generated for the purpose of automatically controlling a different sequence of movements.

The advantage of the device consists in that the cards are not worn out during use in any way, and accordingly remain available for use practically indefinitely.

The possibilities of application of the device described are practically unlimited. In calculating machines for example the device can be used in order to control in succession the various calculation operations desired, such as for example addition, subtraction, multiplication, division, raising to a power, drawing roots, rounding up or rounding down, etc. moreover for storing intermediate results temporarily in a "mechanical electrical memory" (recording), for recalling such intermediate results at a certain moment again from the "memory" and for using them for the further calculation, or for passing intermediate and final results on to another punched card machine, for example for punching the same into a card or tape, etc.

It will be obvious to one skilled in the art that the machine can emit a series of electrical impulses, and then indefinitely repeat again the same series of impulses.

While I have herein described and illustrated in the accompanying drawings what may be considered a typical and particularly advantageous embodiment of my said invention, I wish it to be understood that I do not limit myself to the particular details and dimensions described and illustrated, for obvious modifications will occur to a person skilled in the art.

What I claim as my invention and desire to secure by Letters Patent is:

1. A device for the generation of electric impulses in controlled dependence of a perforated carrier, comprising in combination: a rotatable hollow cylinder having a cylindrical wall, clamping means attaching the perforated carrier detachably to the circumference of the said hollow cylinder to successively produce a desired number of impulse series, the said hollow cylinder being provided with apertures corresponding in number and disposition to the possible places of perforation of the said carrier, at least one stationary source of light and a plurality of stationary photo-electric converters in juxtaposition to those apertures of the said cylinder which are disposed along a

generatrix thereof, light-compartments separated from one another and each containing one of the said photo-electric converters, the said source of light and the said photo-electric converters being separated from one another by the cylindrical apertured wall of the said hollow cylinder.

5 2. A device as claimed in claim 1, comprising in addition: a stationary diaphragm interposed between the said source of light and the said hollow cylinder and having a slot running along a generatrix of the said cylinder.

10 3. A device as claimed in claim 1, wherein the said light source is arranged in the interior of the said hollow cylinder, and comprising in addition: a stationary cylindrical diaphragm arranged between the said source of light and the inner wall surface of the said hollow cylinder 15 and having a slot running along a generatrix of the said cylinder.

4. A device as claimed in claim 1, comprising in addition: a block extending along the said hollow cylinder and over part of the circumference thereof, recesses being provided in the said block forming the said light-compartments.

20 5. A device as claimed in claim 4, wherein the said block comprises several plates stratified side by side, each of the said plates having one of the said recesses forming 25 the said light-compartments.

6. A device as claimed in claim 4, comprising in addition: an elastically yieldable body attached to the said block, the said body being provided with recesses in which the said photo-electric converters are inserted.

30 7. A device as claimed in claim 4, wherein the said recesses flare out from their ends adjacent to the said hollow cylinder towards the said photo-electric converters.

8. A device as claimed in claim 4, wherein the said block and the said photo-electric converters arranged in 35 the recesses thereof are arranged outside the said hollow-cylinder.

9. A device for the generation of electric impulses in controlled dependence of a perforated carrier, comprising in combination: a stationary supporting structure, a 40 holder rotatably mounted on the said structure, a hollow cylinder having a cylindrical wall and detachably mounted cantilever-fashion on the said holder adapted to be fitted thereto and withdrawn therefrom in the axial direction, clamping means attaching the said perforated carrier detachably to the circumference of the said hollow cylinder, the said hollow cylinder being provided with apertures corresponding in number and disposition to the possible places of perforation of the said carrier, at least one stationary source of light and a plurality of stationary photo-electric converters in juxtaposition to those apertures of the said cylinder which are disposed along a generatrix 45 thereof, light compartments separated from one another and each containing one of the said photo-electric converters, the said source of light and the said photo-electric 50 converters being separated from one another by the cylindrical apertured wall of the said hollow cylinder.

55 10. A device as claimed in claim 9, comprising in addition: a stationary hub fixed to the said supporting structure and journaling the said rotatable holder, the said hub 60 being provided with at least one longitudinal passage for the blowing of cooling air and for passing the electrical supply to the said source of light.

11. A device as claimed in claim 9, comprising in addition: an end piece attached to the said rotatable holder, and an end piece attached to the said hollow cylinder, the said end pieces forming together the cooperating parts of a bayonet joint, being adapted to be pushed firstly axially into one another and then turned relative to one another into a mutually interengaging position.

70 12. A device as claimed in claim 10, comprising in addition: spring means biasing the said rotatable holder and the said hollow cylinder axially towards one another into engagement of their end portions forming the said bayonet joint, a recess being provided on the end face 75 of the said end piece of the said hollow cylinder adapted

to allow part of the said spring means to rest itself into.

13. A device for the generation of electric impulses in controlled dependence of a perforated carrier, comprising in combination: a rotatable hollow cylinder having a cylindrical wall and end pieces attached to the said cylinder, overlapping the long edges of the said carrier in the circumferential direction of the said cylinder, one of the said end pieces being detachable from the said hollow cylinder for the purpose of exchanging the said perforated carrier, the said hollow cylinder being provided with apertures corresponding in number and disposition to the possible places of perforation of the said carrier, at least one stationary source of light and a plurality of stationary photo-electric converters in juxtaposition to those apertures of the said cylinder which are disposed along a generatrix thereof, light compartments separated from one another and each containing one of the said photo-electric converters, the said source of light and the said photo-electric converters being separated from one another by the cylindrical apertured wall of the said hollow cylinder.

14. A device for the generation of electric impulses in controlled dependence of a perforated carrier, compris-

ing in combination: a rotatable hollow cylinder having a cylindrical wall and provided with circumferential grooves on one surface and longitudinal grooves on the other surface of its cylindrical wall, the said grooves being deep enough to make transition into one another and to form at their points of intersection apertures corresponding in number and disposition to the possible places of perforation of the said carrier, clamping means attaching the said perforated carrier detachably to the circumference of the said hollow cylinder, at least one stationary source of light and a plurality of stationary photo-electric converters in juxtaposition to those apertures of the said cylinder which are disposed along a generatrix thereof, light compartments separated from one another and each containing one of the said photo-electric converters, the said source of light and the said photo-electric converters being separated from one another by the said apertured cylindrical wall of the said hollow cylinder.
